United States Patent Office

Des. 203,932
Patented Mar. 1, 1966

203,932

CHROMATOGRAPHIC APPARATUS

Egon Stahl, Scheidt, near Saarbrucken, Germany, assignor to Desaga Labor-Technik G.m.b.H., Heidelberg, Germany, a limited-liability company of Germany

Filed Dec. 3, 1964, Ser. No. 82,904

Term of patent 14 years

(Cl. D16—2)

FIG. 1

FIG. 2

FIG. 1 is a perspective front view of the apparatus.
FIG. 2 is a perspective view of the rear of the apparatus.

The bottom, not shown, is a flat cover plate.

The undisclosed underneath portion of the reflector housings is open and plain.

I claim:

The ornamental design for a chromatographic apparatus, as shown and described.
